UNITED STATES PATENT OFFICE.

FREDERIC L. THOMPSON, OF NEW BEDFORD, MASSACHUSETTS, ASSIGNOR
TO THE PAIRPOINT MANUFACTURING COMPANY, OF SAME PLACE.

DESIGN FOR A METALLIC ROSETTE.

SPECIFICATION forming part of Design No. 22,733, dated August 22, 1893.

Application filed January 18, 1893. Serial No. 458,805. Term of patent 7 years.

To all whom it may concern:

Be it known that I, FREDERIC L. THOMPSON, of New Bedford, in the county of Bristol and State of Massachusetts, have invented and produced a new and original Design for a Metallic Rosette, of which the following is a specification, reference being had to the accompanying drawing, showing the same.

The leading feature of my new design is a shield surrounded by flower and scroll work, the flowers and scrolls being arranged circularly and the shield being at one side of the center of the ornament.

A represents a foundation to which my rosette is applied.

B is the pattern which I have invented and produced. It is composed of a shield *b* surrounded by flower work *b'* and scroll work *b''*. The shield is at one side of the middle of pattern B which is substantially circular. 20

What I claim is—

The design for a metallic rosette herein shown and described.

FREDERIC L. THOMPSON.
